DIFFERENTIAL PUMP

André Sobek, Paris, France; vested in the Alien
Property CustodianApplication May 9, 1939, Serial No. 272,665
In Luxembourg February 22, 1939

12 Claims. (Cl. 103—37)

The present invention relates to a liquid pump wherein it is possible to vary the discharge of the pump during rotation thereof without altering the rotating speed. The invention more particularly pertains to a liquid pump which does not require a valve or valves and the operation of which may be reversed.

The liquid pump according to the invention comprises two cylinders which communicate with each other and in which respectively move two pistons having a continuous reciprocating movement, for example respectively actuated against the action of retracting springs by two eccentrics or cams rotating at the same speed, the periodical movements of the two pistons having a lag relatively to each other.

Preferably, the pump is provided with a means which enables the lag between the movements of the two pistons to be varied, either while in operation, or when stopped.

A feature of the pump according to the invention is that the suction and delivery pipes open into the cylinders on the side of the pistons which in this case act as a slide valve. This arrangement enables the suction and delivery valves to be eliminated and the direction of circulation of the liquid through the pump to be reversed by varying the lag between the movements of the pistons.

By way of examples that are in no way limitative, various embodiments of a pump according to the invention, including all or part of the features mentioned above and furthermore exhibiting other remarkable points which also form part of the present invention, have been shown in the accompanying drawing.

In said drawing:

Fig. 1 is a diagrammatical sectional view of a pump according to the invention, of the valve type;

Figs. 2 and 3 are diagrams of the construction and of the operation of a pump according to the invention without a valve;

Figs. 4 and 5 are similar diagrams to those of Figs. 2 and 3 and show a modification of construction;

Fig. 6 is a vertical section of another embodiment of a pump according to the invention;

Figs. 7 and 8 are respectively sections along the lines VII—VII and VIII—VIII of Fig. 6.

In the diagrammatical embodiment of Fig. 1, the pump comprises a block 1 in which are arranged side by side two bores 2 and 3 of the same diameter, which open into a common pipe 4. In said bores or cylinders 2, 3, are mounted

5 respective pistons 5, 6 driven from the end by identical eccentrics 7, 8 which act on said pistons against the action of respective retracting springs 9, 10. Said eccentrics 7, 8 are mounted on the same shaft 11 which rests in bearings 12 carried by the block 1 and is rotated by any means. At least one of said eccentrics, in this case the eccentric 8, is adjustably fixed on the shaft 11, for example by means of a screw 13. The opposite 10 ends of the pipe 4 are respectively connected to pipes 14 and 15 on which are arranged valves 16 and 17 which open in opposite directions to each other.

A kinematic consideration of the system thus 15 formed shows that as the movement of each piston follows a sinusoidal law, the total capacity formed by the parts of the two cylinders 2 and 3 between the pistons and the pipe 4 periodically passes through a maximum and a minimum at 20 each revolution of the shaft 11, unless the eccentrics are set 180° out of phase relatively to each other, since in that case said capacity remains constant and the discharge is zero. When said capacity increases in volume, liquid flows 25 from one of the pipes 14, 15 into the pipe 4 by passing through the corresponding valve 16 or 17. When the capacity decreases, liquid is driven out of the pipe 4 into the other pipe 14, 15 through the corresponding valve. The discharge 30 thus obtained is at a maximum when the two eccentrics 7, 8 are in phase.

It will therefore be seen that it is possible to vary the discharge of said pump, between zero and a maximum, by setting one of the eccentrics 35 out of phase relatively to the other. The direction of circulation of the liquid is determined by the direction of opening of the valves 16 and 17.

In the modification shown in Figs. 2 and 3 the liquid inlet and outlet channels 20, 21 do not 40 open into the pipe 4 which connects the two cylinders 2 and 3 to each other, but each is in open communication with one of the cylinders at a point located approximately at the mid-stroke position of the piston. The pistons 5 and 6 therefore act at the same time as slide valves periodically covering and uncovering the pipes 20 and 21. Furthermore the movement of the piston 6 has a lag of a little more than 180° behind that of the piston 5 and the direction of 45 movement of the pistons in the position in which they are shown has been indicated by arrows. In Fig. 2 the piston 6 has just passed through its extreme high position, whereas in Fig. 3 it is the piston 5 that has nearly reached that position. 50 A kinematic consideration of the general system

shows that the maximum and minimum values of the capacity formed by the cylinders 2 and 3 and the pipe 4 occur at each revolution when the pistons 5 and 6 simultaneously pass through the levels N and N' which are symmetrical with each other relatively to the mid-stroke of the pistons, the difference between said two levels being proportional to the lag of the movements of the pistons. In the position of the pistons shown in Fig. 2, said capacity is increasing in volume and as the pipe 20 is uncovered whereas the pipe 21 is covered by the piston 5, liquid passes from the pipe 20. In Fig. 3 the pipe 21 is uncovered and the pipe 20 is covered, while said capacity is decreasing in volume so that liquid comes out of same through the pipe 21. When the pistons reach the vicinity of the level N', the two pipes 20 and 21 are simultaneously closed and in order to prevent a water-hammering, a discharge valve 24 is provided through which a small amount of liquid escapes at that instant.

In the case in which the lag of the movement of the piston 6 is less than a half-period behind that of the piston 5, the direction of circulation of the liquid would be reversed, the suction in this case taking place through the pipe 21 and delivery through the pipe 20.

In the modification shown in Figs. 4 and 5, one of the suction and of the delivery channels opens into the corresponding cylinder below the extreme low position of the piston and in this case the channel 25 is given a small cross-section. When the channel 20 is uncovered, suction is exerted at the same time in the channels 20 and 25 but it has little effect on the latter owing to its small cross-section, which is very much smaller than that of the channel 20. Delivery is effected through the pipe 25 when the pipe 20 is covered and the capacity decreases in volume. The direction of circulation in this pump is consequently determined by the arrangement of the orifices and cannot be reversed. As there is no danger of water-hammering, the discharge valve 24 provided in the case of Figs. 2 and 3 is eliminated.

In the embodiment shown in Figs. 6 and 8, the eccentrics 31 and 32 which drive the pistons 33 and 34 are fixed in an invariable position on their driving shaft 35 which is rotatably mounted in a casing or pump body 36. The cylinders 37 and 38 in which the pistons 33 and 34 move are formed by two parallel bores in an added part 39 which is fitted in a hole of the pump body 36 and is held in position by the pressure of a hollow plug 40 threaded in the casing 36. The suction and delivery pipes 41, 42 extend to the pump body 36 and open into cavities 43, 44 which are provided in the wall of the casing adjacent the part 39 and which embrace said part over a certain arc. Opposite these grooves 43, 44 respectively open two channels 45, 46 bored in the part 39, one leading to the cylinder 37, the other to the cylinder 38. Said channels 45, 46 open in this case into the cylinders in the manner as provided in Figs. 2 and 3 but they may open therein in any one of the manners provided in Figs. 1, 4 and 5.

The operation of the pump is exactly that of the embodiment of Figs. 2 and 3 but the adjustment of the discharge is effected, when stopped, by varying the angular setting of the part 39 in the casing 36 and for that purpose it suffices to remove the plug 40. It is obvious that by rotating this part 39, the axes of the pistons 33 and 34 are no longer arranged in the same vertical

plane as the axis of the shaft 35 but are located symmetrically on either side of said plane, as shown in Fig. 8, so that a lag is produced between the movements of the two pistons.

5 Of course, the invention is in no way limited to the constructional details illustrated and described which have only been given by way of examples. Thus in particular the pump may be multiple, that is to say comprise more than one group of two pistons co-operating with each other. Similarly the actuating cams or eccentrics may be replaced by a connecting rod and crank drive.

What I claim is:

15 1. A liquid pump of minute output comprising two cylinders in communication with each other, at least one of said cylinders being mounted to rotate about an axis parallel with its own axis, means for securing said last named cylinder in any desired position, inlet and outlet means to and from said cylinders, two pistons respectively movable within said cylinders, spring means urging said pistons in one direction and rotary eccentric or cam means for actuating said pistons against said springs whereby to impart to said pistons reciprocal motions of the same period but having a lag relatively to each other.

20 2. A liquid pump of minute output including a body, provided with a hole, a part mounted in said hole to rotate about an axis, two cylinders formed by bores in said part, said bores being substantially parallel with said axis, a removable hollow plug fitted in said hole and holding said part in position, said cylinders being in communication through the inner part of said hollow plug, inlet and outlet means to and from said cylinders, two pistons respectively movable within said cylinders, spring means urging said pistons in one direction, eccentric or cam means, 25 rotating about an axis substantially at right angle with said axis and actuating said pistons against said spring means whereby to impart to said pistons reciprocal motions having a lag relatively to each other.

30 3. A liquid pump as claimed in claim 1 in which at least the inlet means opens in a cylinder at a point situated approximately midway of the stroke of the associated piston.

35 4. A liquid pump as claimed in claim 2 in which, in order to form said inlet and outlet means, the said part is provided with ports leading to the respective cylinders, corresponding suction and delivery pipes carried by the body, each group of corresponding pipe and port leading to 40 a cavity provided between said hole and said part and embracing said latter over a certain arc.

45 5. A liquid pump as claimed in claim 1 in which said inlet means opens in one cylinder at a point situated approximately midway of the piston stroke while said outlet means opens in the other cylinder at a point also situated approximately midway of the piston stroke, both said pistons being arranged to cooperate with said inlet and outlet means as a slide-valve.

50 6. A liquid pump of minute output comprising two cylinders in communication with each other, inlet and outlet means to and from said cylinders, two pistons respectively movable within said cylinders, spring means urging said pistons in one direction and rotary eccentric or cam means for actuating said pistons against said springs whereby to impart to said pistons reciprocal motions of the same period but having a lag relatively to each other, at least said inlet means 55 opening in the corresponding cylinder at a point

situated approximately midway of the piston stroke and the associated piston is arranged to cooperate with said inlet means as a slide valve.

7. A liquid pump as claimed in claim 6 in which said outlet means opens in the other cylinder at a point also situated substantially midway of the piston stroke.

8. A liquid pump of minute output comprising two cylinders in communication with each other, at least one of said cylinders being mounted to rotate about an axis substantially parallel with its own axis and distant from same, means for securing said cylinder in any desired position, inlet and outlet means to and from said cylinders, two pistons reciprocally mounted within said cylinders and means for reciprocating said pistons.

9. A liquid pump of minute output comprising two cylinders in communication with each other, at least one of said cylinders being mounted to rotate about an axis substantially parallel with its own axis and distant from same, means for securing said cylinder in any desired position,

5 inlet and outlet means to and from said cylinders, two pistons reciprocally mounted within said cylinders, an operating eccentric or cam for each of said pistons rotating about an axis substantially perpendicular to the axis of the corresponding cylinder, and driving means rotating said eccentrics or cams.

10. A liquid pump as claimed in claim 8, in which both cylinders are substantially parallel and are mounted to rotate together about a single axis substantially parallel with their own axis.

11. A liquid pump as claimed in claim 9, in which said two cylinders are parallel and mounted to rotate together about an axis parallel with their own axis, and in which the said driving means includes a common driving shaft on which said eccentrics or cams are mounted.

15 20 25 12. A liquid pump as claimed in claim 1, in which the eccentric or cam means is mounted on a driving shaft arranged substantially perpendicular to said axis and directly engaging the associated pistons.

ANDRÉ SOBEK.
